UNITED STATES PATENT OFFICE.

CARL G. SPRADO, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

INTERNAL-COMBUSTION ENGINE.

Application filed October 7, 1922. Serial No. 593,066.

To all whom it may concern:

Be it known that I, CARL G. SPRADO, a citizen of the United States, residing at Milwaukee, in the county of Milwaukee and 5 State of Wisconsin, have invented a certain new and useful Internal-Combustion Engine, of which the following is a specification.

This invention relates in general to improvements in internal combustion engines, and relates more specifically to improved means for controlling the consistency and admission of explosive mixture to a gas engine or the like.

15 An object of the invention is to provide an improved internal combustion engine which is simple in construction and efficient in operation. Another object of the invention is to provide simple means for effectively controlling the proportions of the ingredients of explosive mixture admitted to a gas engine. A further object of the invention is to provide means for effectively mixing the ingredients of explosive charges delivered to an internal combustion engine. Still another object of the invention is to provide efficient and readily operable means for varying the proportion of the ingredients of explosive mixture admitted to a gas 20 engine and the like. Another object of the invention is to provide means for permitting either manual or automatic accurate variation of the constituents of mixture of explosive fluid. A further object of the invention is to improve the operation and efficiency of gas engine valve gear of the type disclosed and claimed in Patent No. 1,279,774 granted September 24, 1918. These and other objects and advantages of the 25 present invention will be apparent from the accompanying disclosure.

A clear conception of an embodiment of the invention and of the operation of an internal combustion engine constructed in accordance therewith, may be had by referring to the drawings accompanying and forming a part of this specification in which like reference characters designate the same or similar parts in the various view.

30 Fig. 1 is a fragmentary transverse vertical section through the inlet valve mechanism and a cylinder of a gas engine.

Fig. 2 is a fragmentary enlarged horizontal sectional view of the gas engine inlet valve mechanism, the lower part of the view

being a section taken along the line II—II of Fig. 3 and the upper part of the view being a section taken through the gas supply chamber.

Fig. 3 is a fragmentary enlarged part sectional side elevation of a gas engine inlet valve mechanism.

The gas engine illustrated in the drawing is of the horizontal reciprocating type and comprises generally a power cylinder 2, a piston 3 reciprocable within the cylinder 2, a piston rod 4 rigidly associated with the reciprocable piston 3, an explosive mixture admission port 5 communicating with an upper portion of the piston chamber of the cylinder 2, a mixing chamber 28 located above and communicable with the inlet port 5, and suitable mechanism for controlling the admission of gas and air to the chamber 28 and from the chamber 28 to the cylinder 2 through the port 5. A gas supply chamber 8 located adjacent to the upper end of the mixing chamber 28 is communicable with the mixing chamber through a double-ported automatically operative 60 poppet valve 27. An air supply chamber 7 surrounds the medial portion of the mixing chamber 28, the chambers 7, 28 being separated from each other by means of an annular stationary perforated wall 25 and an annular perforated sleeve 24 embracing the wall 25 and adjustable about the vertical axis of annularity of the wall 25. The air supply chamber 7 is constantly in communication with the mixing chamber 28 65 through the perforations in the wall 25 and sleeve 24. The sleeve 24 is supported by means of radial ribs 26 secured to a central hub which embraces a stationary cylindrical vertical wall. The interior of the mixing chamber 28 below the gas inlet valve 27 and the air supply wall 25 and sleeve 24, is provided with a series of helical substantially 70 radial ribs or guide vanes 10 which span the annular passage comprising the lower portion of the chamber 28. Communication between the lower discharge portion 9 of the mixing chamber 28 and the inlet port 5 is automatically controllable by means of a main inlet valve 6 which is normally held 75 in closed position by means of one or more helical compression springs 12.

The mechanism for controlling the operation of the gas supply valve 27 and of the main inlet valve 6 is automatically operable 80

from the lay shaft of the engine by means of a connecting or actuating rod 22. The actuating rod 22 is associated with upper and lower oscillatory levers or arms 20, 17 respectively, the upper arm 20 functioning to actuate the gas supply valve 27 and the lower arm 17 functioning to actuate the mixture admission valve 6. The gas valve actuating rocker arm 20 is pivotally attached 10 to a vertical reciprocable cross-head 18 and has a medial portion engageable with an adjustable fulcrum block 19 supported by the upper extremity of the bonnet 23. The fulcrum block 19 is automatically adjustable in position to vary the degree of opening of the gas inlet valve 27 by means of a governor actuated lay shaft 40 having an eccentric 41 cooperable with a connection 21 associated with the block 19. The vertically reciprocable cross-head 18 is connected to the double-ported gas inlet valve 27 by means of vertical parallel actuating rods 39. The main inlet valve actuating rocker arm 17 is pivotally associated with the bonnet 23 and has a medial portion engageable with a rockable arm 16 one end of which is pivotally associated with the bonnet 23 and which is directly engageable with a knuckle block 15. The knuckle block 15 coacts with a vertically reciprocable cross-head 13 30 slideable in guide ways 14 in the bonnet 23 and secured to the upper extremity of the main inlet valve rod 11. The rod 11 is surrounded by a spring pressed collar coacting with the under side of the cross-head 13 and has the valve 6 rigidly connected to the lower end thereof.

The perforated sleeve 24 located between the air supply chamber 7 and the stationary perforated annular wall 25, is connected to a horizontally slideable adjusting shaft 29 by means of a pin and slot connection 31, so that longitudinal or axial movement of the shaft 29 will produce rotation of the sleeve 24 about the wall 25. An indicating device 30 associated with an end of the shaft 29 and with the stationary casing, provides means for noting the position of the sleeve 24 with reference to the wall 25. The opposite end of the shaft 29 is connected with a lower projection on an eccentric strap 33 having an angularly adjustable eccentric 32 therein which is keyed to the adjusting shaft 38. A lateral arm on the eccentric strap 33 is adjustably connected with an eccentric 35 operable by the governor actuated lay shaft 40 by means of an eccentric strap. The adjusting shaft 38 is adjustably rotatable by means of a crank 42 or similar mechanism operable through a connection 36 by means of a hand wheel 37, a suitable gage 34 serving to indicate the position of adjustment of the shaft 38.

During normal operation of the engine 65 the mechanism having been properly ad-

justed to produce efficient operation, the gas inlet valve 27 is being periodically opened to admit gas downwardly and outwardly from the gas supply chamber 8 to the mixing chamber 28. When a charge of gas has been thus admitted to the mixing chamber 28, the main inlet valve 6 is automatically opened and the suction in the engine cylinder 2 causes the admitted gas to flow toward the inlet port 5. Simultaneously with the downward advance of the gas, air is drawn inwardly from the air supply chamber 7 through the open perforations in the sleeve 24 and wall 25 and intermingles with the gas admitted past the valve 27. The mixture of gas and air is drawn downwardly past the helical mixing vanes 10 and is thoroughly mixed as it enters the final portion 9 of the mixing chamber 28 from which the mixture is delivered past the valve 6 through the port 5 to the engine. In the engine cylinder 2, the explosive mixture thus admitted is ignited to perform useful work upon the piston 3. Such admission of explosive mixture occurs once for each two complete reciprocations of the piston, the admission of mixture being properly timed in a well known manner.

The governor of the engine normally functions in response to variations in speed of the engine, to automatically oscillate the regulating shaft 40 and to vary the positions of the eccentrics 41, 35. As the position of the eccentric 41 is automatically altered by the governor, the position of the fulcrum arm 19 is varied thereby altering the degree of opening of the gas admission valve 27 with a resultant variation in the quantity of gas admitted to the mixing chamber 28. As the eccentric 35 is automatically adjusted by the governor, the eccentric strap 33 is swung about the eccentric 32 causing endwise motion of the shaft 29. Such endwise motion of the shaft 29 is transmitted through the connection 31 at the sleeve 24 and produces variation in the relative position of the perforations in the sleeve 24 and in the adjacent wall 25 thereby either increasing or decreasing the area of the communicating passages between air inlet chamber 7 and the mixing chamber 28. By proper setting of the connection between the lateral projection on the strap 33 and the eccentric strap coacting with the eccentric 35, the relative opening of the gas supply valve 27 and of the air inlet passages, may be adjusted to produce operation of the engine at maximum efficiency and economy. With such adjustment properly made, the speed governor will automatically function to admit explosive mixture having proper proportions of ingredients.

In addition to the adjustment afforded by the lateral projection of the strap 33, the angular position of the shaft 38 and of the ec-

centric 32 may be changed manually by turning the hand wheel 37. This manual adjustment also permits variation in the area of the passages leading from the air inlet chamber

5 7 to the mixing chamber 28, without interfering with the normal operation or adjustment of the gas inlet valve 27 by the governor. It has been found that with the provision of such adjustments, the characteristics of the explosive mixture may be readily and carefully varied to produce maximum efficiency of operation. The helical mixing vanes 10 automatically function to thoroughly mix the ingredients delivered to

10 the chamber 28 in streams flowing oppositely to and impinging directly against each other, and the final mixture delivered from the chamber portion 9 is in intimately mixed condition. The indicating devices 30, 34

15 facilitate adjustment of the sleeve 24 and clearly indicate the position of this sleeve relatively to the wall 25.

It should be understood that it is not desired to limit the invention claimed to the exact details of construction and operation herein shown and described, for obvious modifications within the scope of the claims may occur to persons skilled in the art.

20 It is claimed and desired to secure by Letters Patent:

1. In combination, a cylinder, a mixing chamber communicable with said cylinder, a gas supply chamber communicable with said mixing chamber, a valve for controlling communication between said chambers, an air supply chamber in constant communication with said mixing chamber at a point intermediate said valve and said cylinder, and means oscillatable about the axis of said 25 valve to automatically vary the area of the passage between said air supply and said mixing chambers.

2. In combination, a cylinder, a mixing chamber communicable with said cylinder, a gas supply chamber communicable with said mixing chamber, a valve for controlling communication between said chambers, an air supply chamber in constant communication with said mixing chamber at a point intermediate said valve and said cylinder, means for varying the area of the passage between said air supply and said mixing chambers, and means for producing whirling motion 30 of air and gas admitted to said mixing chamber.

3. In combination, a cylinder, a mixing chamber communicable with said cylinder, a gas supply chamber communicable with said mixing chamber, means for automatically controlling communication between said chambers, an air supply chamber in constant communication with said mixing chamber, and an oscillatory sleeve for automatically varying the area of the passage between said air supply and said mixing chambers.

4. In combination, a cylinder, a mixing chamber communicable with said cylinder, a gas supply chamber communicable with said mixing chamber, an air supply chamber communicating with said mixing chamber, 70 common means for automatically varying the area of the passages between said gas supply and said mixing chambers and between said air supply and said mixing chambers, and means for manually varying only 75 the area of the passage between said air supply and said mixing chambers.

5. In combination, a cylinder, a mixing chamber communicable with said cylinder, a gas supply chamber communicable with 80 said mixing chamber, an air supply chamber in constant communication with said mixing chamber, and a series of helical vanes disposed between said air supply and said cylinder for producing whirling motion of 85 air and gas admitted to said mixing chamber.

6. In combination, a cylinder, a mixing chamber communicable with said cylinder, a gas supply chamber communicable with 90 said mixing chamber, a valve for controlling communication between said chambers, an air supply chamber located in proximity to said mixing chamber, a perforated wall between said air supply and said mixing chamber, 95 a perforated sleeve surrounding said wall, the perforations of said sleeve and wall providing constantly open passages connecting said air supply and said mixing chamber, and means for automatically shifting 100 said sleeve relatively to said wall to vary the area of said passages.

7. In combination, a cylinder, a mixing chamber communicable with said cylinder, a gas supply chamber communicable with 105 said mixing chamber, a valve for controlling communication between said chambers, an air supply chamber located laterally adjacent to said mixing chamber, a perforated annular wall between said air supply and 110 said mixing chambers, a perforated sleeve embracing said wall, the perforations of said sleeve and wall providing constantly open passages connecting said air supply and said mixing chambers, and means for automatically 115 moving said sleeve about the axis of annularity of said wall to vary the area of said passages.

8. In combination, a cylinder, a mixing chamber communicable with said cylinder, a 120 gas supply chamber communicable with an end of said mixing chamber, an automatically operable valve for controlling communication between said chambers, an air supply chamber surrounding said mixing 125 chamber, a perforated annular wall between said air supply and said mixing chambers, a perforated sleeve embracing said wall, the perforations of said sleeve and wall providing constantly open passages connecting said 130

air supply and said mixing chambers, means for automatically moving said sleeve about the axis of annularity of said wall to vary the area of said passages, helical vanes for producing whirling motion of gas and air admitted to said mixing chamber, and an automatically operable valve for controlling communication between the opposite end of said mixing chamber and said cylinder.

10 9. In combination, a cylinder, a mixing chamber communicable with said cylinder, a gas supply chamber communicable with said mixing chamber, a valve for controlling communication between said chambers, an air supply chamber in constant communication with said mixing chamber at a point intermediate said valve and said cylinder, means for varying only the area of the passage between said air supply and said mixing chambers, and a valve for controlling communication between said mixing chamber and said cylinder.

10 10. In combination, a cylinder, a mixing chamber communicable with said cylinder, a gas supply chamber communicable with said mixing chamber, means for automatically controlling communication between said chambers, an air supply chamber in constant communication with said mixing chamber, means for varying only the area of

the passage between said air supply and said mixing chambers, and means for automatically controlling communication between said mixing chamber and said cylinder.

11. In combination, a cylinder, a mixing chamber communicable with said cylinder, a gas supply chamber communicable with said mixing chamber, an air supply chamber communicating with said mixing chamber, means for manually varying only the area of the passage between said air supply and said mixing chambers, and means for automatically establishing communication between said mixing chamber and said cylinder.

12. In combination, a cylinder, a mixing chamber communicable with said cylinder, a gas supply chamber communicable with said mixing chamber, automatically operable means for intermittently establishing communication between said chambers, an air supply chamber in constant communication with said mixing chamber, means for controlling communication between said air supply and said mixing chambers, and means for both manually and automatically adjusting said air supply control means.

In testimony whereof, the signature of the inventor is affixed hereto.

CARL G. SPRADO.
